DESIGN FOR A GRILL UTENSIL

John L. Bennett and Stephen A. Platt,
Decatur, Ill.

Application March 6, 1934, Serial No. 50,968

Term of patent 7 years

To all whom it may concern:

Be it known that we, John L. Bennett and Stephen A. Platt, citizens of the United States and residents of Decatur, county of Macon, and State of Illinois, have invented a new, original, and ornamental Design for a Grill Utensil, of which the following is a specification, reference being had to the accompanying drawing, forming part thereof.

In the drawing—

We claim:

The ornamental design for a grill utensil as shown and described.

JOHN L. BENNETT.
STEPHEN A. PLATT.
